UNITED STATES PATENT OFFICE.

CHARLES D. ALLAN, OF CHICAGO, ILLINOIS.

FIRE-EXTINGUISHER.

1,131,498.

Specification of Letters Patent.

Patented Apr. 6, 1915.

Application filed November 8, 1914. Serial No. 370,373.

To all whom it may concern:

Be it known that I, CHARLES D. ALLAN, a citizen of the United States, and a resident of Chicago, in the county of Cook and State of Illinois, have invented a certain new and useful Improvement in Fire-Extinguishers, of which the following is a specification.

This invention relates to fire extinguishers and relates particularly to valves for controlling the admission of water to automatic sprinkler systems, of the type known as dry-pipe valves.

One form of dry-pipe valve which has been used to a very large extent, is what is known as a differential valve, in which a relatively small water admission opening is closed by a valve which is secured in closed position against a relatively high water pressure in the main or other source of supply of water under pressure by a relatively large air valve which is exposed to an unbalanced relatively low air pressure in the sprinkler system. As heretofore constructed, the operation of valves of this type has been objectionable because, when the valve opens and water is admitted to the sprinkler system such water will form a water column, the pressure of which acting on the relatively large air valve, with the weight of the valves, will, under certain conditions, cause said valves to become reseated and will prevent reopening thereof until the system has been drained. This is known as "columning" and is such a serious objection that it has been found necessary to provide supplementary mechanical means for its prevention, and various devices for this purpose have been designed and patented, but seem to have met with only indifferent success.

The primary object of the present invention is to provide a construction for a dry-pipe valve of the differential type whereby "columning" will be prevented.

Further objects of the invention are to provide a dry-pipe valve which will be simple in construction, cheap to manufacture as compared with any dry-pipe valve of which I have any present knowledge; and which will be effective and reliable for its designed purpose.

To effect the foregoing objects, a dry-pipe valve of my invention comprises the various features, combinations of features and details of construction hereinafter described and claimed.

In the accompanying drawing in which

my invention is fully illustrated, Figure 1 is a central, vertical, sectional view of a dry-pipe valve embodying my invention, the valves being shown closed in full lines and in open position in dotted lines. Fig. 2 is a sectional, plan view on the line 2-2 of Fig. 1; and Fig. 3 is a fragmentary view from the position 3-3 of Fig. 2.

Referring now to the drawings, A designates the valve casing which, for convenience and economy of manufacture is made in two separate sections, designated, respectively, A¹ and A², and which are detachably connected by means of cap screws or the like inserted through flanges *a* formed on the connected ends of said casing sections.

At its lower end, the casing A is provided with a water admission opening 1 which is adapted to be connected to a water main or other source of supply of water under pressure and, at its upper end, said casing is provided with a discharge opening 2 which is adapted to be connected with a sprinkler system.

Surrounding the water admission opening 1 within the valve casing is a valve seat 3 co-operating with which is a valve 4 provided with a seat 5 corresponding to the valve seat 3. To provide for moving the valve 4 into closed and opened positions, said valve is hinged to a support rigidly attached to the valve casing, the relation being such that when said valve is fully open it will be entirely out of the water way and accidental reseating thereof effectually prevented, that is, it will be in stable open position.

A tight joint between the valve seats 3 and 5 can readily be formed by grinding the same together with emery powder or the like, in the familiar manner, and, in order to centralize the valve seat 5 relatively to the valve seat 3 when the valve 4 is subjected to pressure, in the manner presently described, the valve seats 3 and 5 are correspondingly inclined or beveled. Also, limited play is preferably provided in the valve hinge in order that the valve seat on said valve may accommodate or adjust itself to the valve seat 3 so as to insure a tight joint.

In the preferable construction shown the valve seat 3 is formed at the upper end of what may be appropriately termed a nipple 6, which forms a tubular extension of the water admission opening 1 upwardly within the casing A. Preferably, also, said nipple 6 is made separate from the valve casing

A and is bolted or otherwise detachably connected thereto, thus making provision for finishing, assembling and fitting said nipple 6 and valve 4 as separate operations before 5 they are placed into the casing A, and also for detaching and removing the same in case it becomes necessary at any time to regrind the valve seats 3 and 5.

As shown, the valve 4 is hinged to a boss 7 formed on the upper end of the nipple 6 by means of a yoke 8, bolted or otherwise detachably connected to the valve 4, formed on which are bosses 9, said bosses 7 and 9 being provided with alined bearings for the hinge 15 pin 10, and the bearing in one thereof being fitted loosely to provide for limited play of said valve 4 to permit the valve seat 5 thereon to seat itself accurately upon the valve seat 3. With the described construction, it is 20 obvious that, by disconnecting the yoke 8 from the valve 4, said valve will be free to turn on its longitudinal axis, thus providing for conveniently grinding the valve seats 3 and 5 together.

25 The nipple 6 is made of such height that the valve 4 may be turned practically through 180 degrees, into the position shown in dotted lines, Fig. 1, with its upper end resting against the lower end wall of the 30 casing A.

For reasons presently explained, the outer surface of the valve 4 is made substantially conoidal, the relation being such that the distance from the axis of the hinge pin 10 35 to the top of said valve 4 will exceed the distance from the axis of said hinge pin to any other part of said valve.

In operation, the valve 4 is adapted to be maintained closed against the force of the 40 water pressure in the main or other source of supply of water, by means of a differential air valve which, in use, is subjected to the air pressure in the sprinkler system, and a rigid part of which is adapted to bear 45 upon the valve 4 when in closed position, the relation being such that the normal air pressure on said air valve will maintain the valve 4 closed against the water pressure to which it is subjected. While my invention 50 contemplates the use of any suitable air valve for thus securing said valve closed, I prefer the form of valve shown in the drawings, which for purposes of convenient reference is designated, as a whole B, and 55 which I will now describe. Formed on the interior of the casing A is a flange a^1 , bolted or otherwise secured to which is a ring 11 provided with a valve seat 12. The movable member of said air valve comprises a float 60 13, which preferably consists of an air-tight, hollow, aluminum sphere. Formed around said float 13 is a flange 14, the outside diameter of which is slightly less than the inside diameter of the ring 11, and secured thereto 65 is a flat ring of suitable flexible material, as

rubber, leather or the like, and which extends outwardly over the valve seat 12 and, in operation, is adapted to be held in close contact with said valve seat by the air pressure in the sprinkler system. Secured in the 70 float 13 and extending downwardly therefrom is a rod or valve stem 15, the lower end of which is adapted to bear on the top of the valve 4, said valve stem being preferably connected to said float in such manner that 75 it may be adjusted to extend a greater or less distance below said float. As shown, said valve stem is made separate from said float and is secured in screw threaded engagement with a hole formed in a boss 16 80 on said float and is adapted to be secured in different adjusted positions therein by a usual lock-nut 17.

The movable member B of the air valve is guided in its operative movement and 85 maintained in operative position, by a bearing in a fixed boss 18 to which the valve stem 15 is fitted so as to be freely movable endwise. As shown, said boss 18 is secured in position by downwardly-curved arms 19 90 which connect said boss with the ring 11.

Formed on the valve stem 15 is a head 20 contact of which with the lower end of the boss 18 is adapted to limit the movement of the air valve B above its seat, while the upper end of the boss 18 is so positioned that, when the lower end of the valve stem 15 rests on the valve 4, when in closed position, the lock-nut 17 will be only a slight distance above the upper end of said boss, 100 say about $\frac{1}{2}$ of an inch, thus limiting the downward movement of the movable air valve member B. By flattening the sides of the head 20 so that it may be conveniently grasped by a wrench, convenient means are 105 provided for screwing the valve stem into screw threaded hole in the boss 16 and for adjusting the same therein.

With the described construction, it is obvious that the air valve, when closed, will 110 divide the interior of the casing A into an upper compartment A², which is in open communication with the sprinkler system, and a lower compartment A⁴ with which the admission opening 1 communicates directly.

The diameter of the air valve is several times that of the inside diameter of the admission opening 1, a desirable relation in practice being about 4 to 1, so that the area 120 of the air valve exposed in the chamber A³ and which is subjected to the air pressure in the sprinkler system will be more than twelve times the area of the water admission opening 1. It is thus obvious that a 125 relatively very small air pressure in the sprinkler system will hold the valve 4 closed against the water pressure in the water main or other source of water supply.

When the dry-pipe valve is set for opera- 130

tion, the valve 4 and the air valve will be in the positions shown in full lines, Fig. 1, in which position they will be maintained by the air pressure in the sprinkler system. 5 When, however, one of the sprinklers of the sprinkler system opens, the sprinkler system will be vented, whereby the water pressure on the valve 4 will cause both said valve 4 and the air valve B to open, thus 10 permitting the water to flow freely through the casing A from the water main or other source of water supply into the pipes of the sprinkler system. It is apparent that the in-rush of water through the admission opening 1, will operate to turn the valve 4 and to raise the air valve B into the positions shown in dotted lines in Fig. 1, in which position said valve 4 will be entirely out of the water way and in stable open 15 position so that accidental reseating thereof will be absolutely impossible, and the current of water passing through the valve casing and the buoyancy of the float 15 will operate to maintain the float or air valve in 20 its extreme raised position. If, for any reason, the supply of water should be cut off temporarily, thus producing an unbalanced column of water in the sprinkler system, the buoyancy of the float 13 would prevent reseating of the air valve B.

As heretofore stated the valve 4, when once opened can only be reset or reseated by hand and to provide for thus resetting or reseating said valve, the valve casing A 35 is provided with a hand-hole 22 which is closed by a removable cover 23.

In use, my improved valve will be provided with suitable drain connections, alarm devices and the like. These, however, can 40 readily be supplied by any person familiar with the construction and operation of such devices and need not, therefore, be described in detail and for that reason are not shown in the drawings.

45 With the described construction of the valve 4 and the manner of hinging the same, whereby the distance from the axis of the hinge to the top of the valve is greater than the distance from the axis of said hinge to other parts of the valve, it is obvious that 50 when the rod 14 has raised a sufficient distance to permit the upper end of said valve to pass out of engagement with said rod 14, all other parts of said valve will swing 55 clear of the lower end of said rod as said valve 4 opens.

I claim:-

1. In a dry-pipe valve, the combination of a casing provided with admission and discharge openings, a valve adapted for closing said admission opening, means for movably supporting said valve whereby water under pressure entering the casing through the admission opening thereto will move 60 said valve into stable open position, a dif-

ferential air valve a rigid part of which is adapted to bear on the valve applied to the admission opening to said casing, and means for guiding the movement of said air valve, substantially as described. 70

2. In a dry-pipe valve, the combination of a casing provided with admission and discharge openings, a valve adapted for closing said admission opening, means for movably supporting said valve whereby water under pressure entering the casing through the admission opening thereto will move 75 said valve into stable open position, a differential air valve a rigid part of which is adapted to bear on the valve applied to the admission opening to said casing, means for guiding the movement of said air valve, and a float applied to said air valve for imparting buoyancy thereto, substantially as described. 85

3. In a dry-pipe valve, the combination of a casing provided with admission and discharge openings, a nipple which surrounds said admission opening within said casing, a valve hinged to said nipple and adapted for closing the open end thereof, the relation being such that water under pressure entering said casing through said nipple will turn said valve into stable open position, a differential air valve a rigid part of 90 which is adapted to bear on the valve hinged to said nipple, and means for guiding the movement of said air valve, substantially as described. 95

4. In a dry-pipe valve, the combination of a casing provided with admission and discharge openings, a nipple which surrounds said admission opening within said casing, a valve hinged to said nipple and adapted for closing the open end thereof, the relation being such that water under pressure entering said casing through said nipple will turn said valve into stable open position, a differential air valve a rigid part of 100 which is adapted to bear on the valve hinge to said nipple, means for guiding the movement of said air valve, and a float applied to said air valve for imparting buoyancy thereto, substantially as described. 105

5. In a dry-pipe valve, the combination of a casing provided with admission and discharge openings, a detachable nipple which surrounds said admission opening within said casing, a valve hinged to said nipple and adapted for closing the open end thereof, the relation being such that water under pressure entering said casing through said nipple will turn said valve into stable open position, a differential air valve a rigid part 110 of which is adapted to bear on the valve hinged to said nipple, and means for guiding the movement of said air valve, substantially as described. 115

6. In a dry-pipe valve, the combination of a casing provided with admission and dis- 120

- charge openings, a detachable nipple which surrounds said admission opening within said casing, a valve hinged to said nipple and adapted for closing the open end thereof, the relation being such that water under pressure entering said casing through said nipple will turn said valve into stable open position, a differential air valve a rigid part of which is adapted to bear on the valve hinge to said nipple, means for guiding the movement of said air valve, and a float applied to said air valve for imparting buoyancy thereto, substantially as described.
7. In a dry-pipe valve, the combination of a casing provided with admission and discharge openings, a detachable nipple which surrounds said admission opening within said casing, a valve hinged to said nipple adapted for closing the open end of said nipple, said hinge comprising a hinge plate detachably connected to said valve, whereby said valve may be disconnected from said nipple and turned axially relatively thereto to provide for grinding the valve seats on said nipple and valve together, a differential air valve a rigid part of which is adapted to bear on the valve hinged to said nipple, and means for guiding the movement of said air valve, substantially as described.
8. In a dry-pipe valve, the combination of a casing provided with admission and discharge openings, a detachable nipple which surrounds said admission opening within said casing, a valve hinged to said nipple adapted for closing the open end of said nipple, the valve seats on said nipple and
- valve being correspondingly inclined and the hinge joint being loosely fitted to provide for limited play of said valve and said hinge comprising a hinge plate detachably connected to said valve, whereby said valve may be disconnected from said nipple and turned axially relatively thereto to provide for grinding the valve seats on said nipple and valve together, a differential air valve a rigid part of which is adapted to bear on the valve applied to the admission opening to said casing, and means for guiding the movement of said air valve, substantially as described.
9. In a dry-pipe valve, the combination of a casing provided with admission and discharge openings, a valve adapted for closing said admission opening, a differential air valve comprising a float, a valve seat formed thereon, a stem adjustably secured in said float and which projects downwardly therefrom adapted to bear on the valve applied to the admission opening to said casing, and a rigidly supported bearing boss provided with a bearing to which said valve stem is fitted so as to be freely movable endwise therein, substantially as described.

In testimony that I claim the foregoing as my invention, I affix my signature in the presence of two subscribing witnesses this 5th day of November, 1914.

CHARLES D. ALLAN.
